UNITED STATES PATENT OFFICE.

HANS VASDAHL, OF SWISSVALE, PENNSYLVANIA, ASSIGNEE TO McCLINTIC-MARSHALL COMPANY, OF PITTSBURGH, PENNSYLVANIA, A CORPORATION OF PENNSYLVANIA.

ADJUSTABLE RAIL-CLAMP.

1,252,971.

Specification of Letters Patent.

Patented Jan. 8, 1918.

Application filed November 7, 1917. Serial No. 200,678.

To all whom it may concern:

Be it known that I, HANS VASDAHL, a citizen of the United States, residing at Swissvale, in the county of Allegheny and State 5 of Pennsylvania, have invented certain new and useful Improvements in Adjustable Rail-Clamps, of which the following is a specification:

My invention relates to improvements in 10 clamping or fastening devices, and more particularly to adjustable devices of the character mentioned designed to be employed for adjustably securing locomotive, traveling crane, or other moving vehicles or machinery track rails to steel girders, beams, stringers, or other carrying members.

In such constructions it is frequently necessary to adjust the position of the rails 20 relatively to the center line of the load carrying members, and the prime object of the present invention is to provide simple and efficient means to enable such adjustments to be readily and accurately made.

In the accompanying drawings which 25 illustrate applications of my invention,

Figure 1 is a vertical sectional view showing a rail, rail supporting members, and my invention applied thereto;

Fig. 2 is a top plan view embodying my 30 invention with the rail and supporting members omitted;

Fig. 3 is a detail view showing an apertured disk or washer member; and

Fig. 4 is a similar view showing the cap 35 member employed in my construction.

Referring to the drawings, 2 designates a rail and 3 a supporting member in the form of a girder having a plate 4 mounted thereon and designed to receive the base portion 40 of the rail 2.

The clamping or fastening device, as illustrated and as preferred, comprises a plate or body portion 5 formed with a plurality of circular openings 6 and having a slightly 45 upwardly inclined projection 7 designed to conform to the configuration of the upper surface of the rail base and a portion of the web of the rail. While I have shown two openings 6 in the body portion, it will be 50 evident that a single opening or more than two openings may be employed. In practice, these fastening or clamping devices are disposed at suitable intervals on both sides of the track.

55 Located within each opening 6 of the body

portion is an eccentrically mounted element, disk or washer 8. In addition to the bolt receiving hole 9 the eccentrically mounted element is provided with tool engaging means 10. As shown, the tool engaging means consists of a hole, slot or other opening formed in the periphery of the said element. The eccentrically mounted element 8 is designed to rest within the opening 6 upon a filler piece 11 disposed between the plate 4 and the under side of the body 5, said filler as well as the plate 4 having alined openings 12 and 13 to receive a bolt 14.

15 designates a cap or cover designed to fit over the eccentrically mounted element 8. This cap is provided with an eccentrically disposed opening 16 through which the bolt 14 is inserted in securing the parts together. Said cap is also formed with a tool engaging opening 17, said opening being designed when the cap is in one position relatively to the eccentrically mounted member 8 to register with the opening or slot formed therein, thereby enabling member 8 and cap 15 to be moved in unison by means 70 of a suitable tool or wrench 18. The wrench or tool, as illustrated, has an end portion 19 suitably formed to embrace the head or nut of the securing bolt 14 and is further provided with a downwardly projecting lug 20 75 designed to engage the means 10 of the eccentrically mounted element and the walls of the opening 17 of the cap.

While it is designed to move the cap and element 8 together in effecting the desired 80 adjustments, it should be understood that the cap may be moved independently of the element in order to move the opening 17 out of register with the tool engaging means of the said element.

95 In Fig. 1, it will be noted that the position of the parts shows the rail adjusted inwardly relatively to the center line *a* of the carrying member, to its extreme inward position. The adjustment of the rails into the 100 position illustrated, as well as the adjustment in the opposite direction, may be readily and accurately effected by turning the eccentrically mounted element by manipulating the tool or wrench.

105 What I claim is:

1. An adjustable clamping device for rails including a body member having a circular opening, an eccentrically mounted element provided with tool engaging means disposed 110

- in the opening, and a bolt passed through the said body member and element.
2. An adjustable clamping device for rails including a body member having a circular opening, an eccentrically mounted element disposed in the opening, a cap mounted on the body over its opening, and a bolt passed through said cap, body and element.
3. An adjustable clamping device for rails including a body member having a circular opening, an eccentrically mounted element provided with tool engaging means disposed in the opening, a cap mounted on the body over its opening, and a bolt passed through said cap, body and element.
4. An adjustable clamping device for rails including a body member having a circular opening, an eccentrically mounted element provided with tool engaging means disposed in the opening, a cap mounted on the body over its opening and having tool engaging means registering with the tool engaging means of the body, and a bolt passed through said cap, body and element.
5. An adjustable clamping device for rails including an upper body member having a circular opening, a lower member on which the base of the rail rests, an eccentrically mounted element disposed in the opening of the body and provided with tool engaging means, a filler between the lower member and the eccentrically mounted element, and a bolt passed through the body member, filler and lower member.
6. An adjustable clamping device for rails including an upper body member having a circular opening, a lower member on which the base of the rail rests, an eccentrically mounted element disposed in the opening of the body and provided with tool engaging means, a cap mounted on the body over its opening, a filler between the lower member and the eccentrically mounted element, and a bolt passed through the cap, body member, filler and lower member.
7. An adjustable clamping device for rails including an upper body member having a circular opening, a lower member on which the base of the rail rests, an eccentrically mounted element disposed in the opening of the body and provided with tool engaging means, a cap mounted on the body over its opening, a filler between the lower member and the eccentrically mounted element, and a bolt passed through the cap, body member, filler and lower member.
8. Means for securing rails to load carrying members and for adjusting the rails relatively to the center line of said members comprising upper and lower plate members, said upper plate having a washer receiving opening, an eccentric washer having tool engaging means disposed in said opening, 60 and a bolt passed through the plate members and washer.
9. Means for securing rails to load carrying members and for adjusting the rails relatively to the center line of said members comprising upper and lower plate members, said upper plate having a washer receiving opening, an eccentric washer having tool engaging means disposed in said opening, a 65 cap having tool engaging means covering the opening of the upper plate, and a bolt passed through the cap, plate members and washer.
10. Means for securing rails to load carrying members and for adjusting the rails relatively to the center line of said members comprising upper and lower plate members, said upper plate having a washer receiving opening, an eccentric washer having tool engaging means disposed in said opening, a 70 cap having tool engaging means covering the opening of the upper plate, and a bolt passed through the cap, plate members and washer.
11. Means for securing rails to load carrying members and for adjusting the rails relatively to the center line of said members comprising upper and lower plate members, said upper plate having a washer receiving opening, an eccentric washer having tool engaging means disposed in said opening, a 75 cap having tool engaging means covering the opening of the upper plate, and a bolt passed through the cap, plate members and washer.
12. Means for securing rails to load carrying members and for adjusting the rails relatively to the center line of said members comprising upper and lower plate members, said upper plate having a washer receiving opening, an eccentric washer having tool engaging means disposed in said opening, a 80 cap having tool engaging means covering the opening of the upper plate, and a bolt passed through the cap, plate members and washer.
13. Means for securing rails to load carrying members and for adjusting the rails relatively to the center line of said members comprising upper and lower plate members, said upper plate having a washer receiving opening, an eccentric washer having tool engaging means disposed in said opening, a 85 cap having tool engaging means covering the opening of the upper plate, and a bolt passed through the cap, plate members and washer, said tool engaging means of the cap and washer adapted to be engaged by a common tool and moved in unison.
- In testimony whereof I affix my signature in presence of two witnesses.

HANS VASDAHL
